METHOD FOR GEOPHYSICAL PROSPECTING

Charles A. Moon, Caracas, Venezuela, assignor to
Socony-Vacuum Oil Company, Incorporated,
New York, N. Y., a corporation of New York

Application March 12, 1942, Serial No. 434,421

9 Claims. (CL 250—83.6)

This invention relates generally to methods of geophysical prospecting especially applicable to the exploration of earth openings such as well bores and the like. More particularly, it is concerned with methods of gauging the geological nature of subterranean earth formations during, and without substantial interruption of, well bore drilling operations.

In the removal of useful natural deposits, particularly materials of petroleum origin, from the geological formations wherein they naturally occur, it is usual, after selection of a suitable locality for operations, to drill a well bore in the earth to a depth such that a satisfactorily productive stratum is encountered or the nonproductive nature of the region is definitely established. As experience of workers in this field indicates, the presence of productive strata can be predicted with acceptable accuracy after knowledge of the geological character of strata encountered has been obtained by logging the well in accordance with any of the methods now commonly used. It will be apparent, accordingly, that the drilling and prospecting operations should desirably be performed simultaneously in order that the drilling crew may be warned of the probable occurrence of a productive strata in the vicinity of drilling operations, thus permitting them to make ready suitable equipment to prevent waste of discharged oil.

However, most present day methods of geophysical prospecting having as an object to provide data indicative of the character of strata traversed by a well bore are intended to be or, as a practical matter, are performed after the drilling operations have ceased, the drill stem has been removed and the drill operating apparatus has been removed from the mouth of the well bore. This practice, although very costly because it causes interruption of the drilling schedule and wastes the time of the drilling crew, is due to the inherent difficulties, chiefly in matters of the design and construction of suitable equipment, that preclude conducting the prospecting operations while the drill stem is in operative position within the bore. Furthermore, many methods of prospecting, based on characteristics of geological formations such as specific resistivity, chemical analysis, alteration of electrical fields, and the like, widely relied upon by workers in the field, cannot be performed satisfactorily within a metallic sheath such as the drill stem would constitute, thus necessitating previous removal of the stem and the associated equipment.

Even assuming that suitable equipment were

available, an additional difficulty of a practical nature makes it undesirable to perform ordinary prospecting operations during drilling of the well bore because these operations in almost every instance entail the time-consuming procedure of lowering the prospecting instrument within the bore at a slow rate of travel adequate for delicate measurements to be obtained with the requisite accuracy and sensitivity, and thereafter withdrawing the instrument and associated cables from the drill stem. Both of these operations, of necessity, would be conducted while the drill stem is chucked off the well bottom and held motionless in the well, thus interrupting and delaying the schedule of the drilling crew and materially increasing the expenditures necessary before the productivity or non-productivity of the well could be established with reasonable certainty. For the foregoing and other reasons, the conducting of well logging operations without removal of the drill stem, although long recognized as being a desirable and economically advantageous procedure, heretofore has not been commercially practiced by workers in this field.

The present invention now provides a method of geophysical prospecting that can be practiced during the usual course of drilling operations without giving rise to delays interrupting the drilling schedule. In practicing the invention, a geophysical prospecting device, preferably of the type sensitive to high frequency radiation, is moved within a bottom portion of the well bore at the time of adding each successive new drill stem element to the drill string, thereby providing the operators with immediate indications of the character of substrata being traversed by the bore. It thus becomes possible, in accordance with this invention, wholly to obviate logging of the well subsequent to drilling, thereby effecting economies not merely during the drilling operations but also subsequent thereto as the well is being prepared for actual production.

To facilitate a better understanding of the present invention and of how the same may be practiced during field operations, a specific embodiment thereof, presented by way of example but not by way of limitation, will be hereinafter described.

In the accompanying drawing the presently preferred embodiment of the instant invention is illustrated, but it is clearly to be understood that the scope of this invention is not to be restricted to this particular embodiment thereof except insofar as is indicated in the subjoined claims.

Referring to the drawing:

Figure 1 is essentially a diagrammatic illustra-

tion of a well bore and portions of a well super-structure associated therewith, during an early stage of drilling and prospecting operations;

Figure 2 is a similar view illustrating a later stage of operations including the addition of a length of drill stem to the partially withdrawn drill string;

Figure 3 is a view similar to the foregoing wherein the added length of drill stem is shown within the well bore and connected into the string; and

Figure 4 is essentially a diagrammatic illustration of a prospecting instrument suitable for employment in the practice of this invention.

In well drilling operations, additional lengths of drill stem are coupled successively into the drill string as the bit progresses into subterranean formations. These additional drill stem elements are usually introduced into the string by withdrawing the string partially from the well, both to facilitate attachment of the new element and to prevent sticking or freezing of the bit on the floor of the well bore, adding the element, and then returning the string to operative position within the well bore. In accordance with the present invention, the prospecting operations are conducted while additional stem elements are being incorporated in the drill string as will hereinafter appear.

In Figures 1, 2, and 3 of the accompanying drawing, a well bore 10 is illustrated, within which is positioned a drill string 11 carrying a drill bit 12. The drill string is driven during drilling operations by a rotating table 13, coupled to the string through a freely vertically slideable Kelly bar 14, connected to a kelly 15 in the conventional manner.

In Figure 1 of the drawing an initial stage in the sequence of drilling and prospecting operations according to this invention is illustrated, wherein the drill stem 11 is shown positioned within the well bore 10 with the drilling bit 12, mounted upon the end of the drill string, resting in operative position upon the bottom 10a of the bore. It is to be understood that the Kelly bar 14 which engages with and is rotated by the table 13, is connected through the kelly 15 to a suitable source of drilling mud in the conventional manner. During the drilling operation the table 13 is rotated, thereby rotating the drill string and causing it to move downwardly as the bit bites through the subterranean earth formations. These operations are continued until the kelly 15 closely approaches the rotating table 13, as illustrated in Figure 1, at which time operations are interrupted and the drill stem is partially withdrawn from the well bore for addition of a further drill stem element to the string.

A second stage in the drilling operations, illustrated in Figure 2, includes the addition of a length of drill stem to the string as above mentioned. The additional drill stem element 16 is shown attached to the Kelly bar 14, which is permanently connected to the kelly 15 as above described. At this stage of the operations the drill bit 12 has been raised from the floor 10a of the well bore 10, both to avoid sticking and to permit introduction of the additional stem element at the junction of the Kelly bar and the drill string, and is retained in raised position 70 by chucking the string at the rotating table 13. In accordance with the present invention, while the drill string is thus held and before the additional stem element 16 is attached thereto, a prospecting instrument 17, hereinafter described,

is placed within the string in a manner such that it rests in a preselected position within the stem near the base thereof substantially as shown. As will be apparent to those versed in this art, the instrument can, if desired, be dropped within the drill stem and permitted to fall into the desired position or can be lowered upon a cable, which can be disengaged from the instrument when the same has reached the desired position near the drill bit.

Following the above-described operations, the additional drill stem element is coupled to the portion of the drill string held in the rotary table 13 and the assembly then is lowered within the well bore to place the drill bit 12 near its operative position against the bore bottom 10a. Inasmuch as the prospecting instrument 17 remains in its preselected position within the drill stem during these operations, as the drill string is lowered within the well bore the instrument is moved from its initial position illustrated in Figure 2 to a position nearer the bottom of the well bore. The rate of lowering of the drill string within the bore with corresponding movement of the prospecting instrument is carefully controlled for reasons which will be hereinafter mentioned.

Following the lowering of the drill string within the well bore as described, the prospecting instrument is removed therefrom by use of a suitable fishing device. For this purpose the drill string can be opened either by disengagement of the kelly 15 from the Kelly bar 14 or by disengaging the Kelly bar from the top stem element, whichever is convenient under the conditions of operation. Thereafter the kelly or Kelly bar, removed during the fishing, is recoupled to the bar or stem respectively and drilling operations can then proceed in the conventional manner.

Following this sequence of operations and the removal of the prospecting instrument as mentioned, the equipment is disposed within the well bore substantially as illustrated in Figure 3, in readiness for further drilling of the well bore, with the only interruption in the normal drilling operations occurring at the time of removal of the instrument. This brief interruption, as a practical matter, is of negligible importance.

The prospective instrument 17 employed in the practice of this invention as above described is diagrammatically illustrated in Figure 4 and comprises a fluid-tight capsule or envelope 20, provided at its top end with an irregularly shaped projecting member 21 capable of readily engaging with a fishing cable to facilitate removal of the instrument from the drill stem as mentioned. Within the capsule 20 are provided a control unit 22, a signal transmitter or recorder 23, and a geophysical prospecting device 24, suitably interconnected and interrelated as will be hereinafter described.

The geophysical prospecting device 24 can be any one of the several types of instruments that are capable of detecting characteristics of nearby geological formations despite the presence of relatively large masses of metal such as the drill stem which, in the practice of this invention, surrounds the instrument during use. More particularly, the prospecting device can be an instrument for detecting, qualitatively and/or quantitatively, natural, artificially induced, or reflected radiation emanating from the neighboring geological formations under investigation. A typical device for this purpose comprises an

ionization chamber containing differentially electrically charged electrodes within a dielectric, usually an inert gas under superatmospheric pressure, capable of being ionized by radiation from nearby strata whereby a measurable proportionally related current flows between the electrodes. The current thus produced is transmitted in accordance with usual practice to an amplifier in order that the magnitude thereof may be materially increased, thus facilitating use of the signals from the device to control other equipment, particularly recorders or the like. Prospecting devices of this nature are disclosed in the Patent No. 2,133,776, granted to John C. Bender, October 18, 1938, and in the copending applications of Jacob Neufeld, S. N. 161,350, filed August 27, 1937, and S. N. 279,964, filed June 7, 1939. The prospecting device used can also if desired be of a type capable of detecting primary or secondary neutron streams emanating from geological formations. This type of prospecting instrument is similar in principle and construction to that above described except that the ionization chamber is provided with a suitable surfacing material capable, by interaction with neutron streams, of causing ionization of the dielectric within the chamber. A typical device of this nature is disclosed in the patent to Folkert Erons, No. 2,220,509, granted November 5, 1940, and in the patent to Robert E. Fearon, No. 2,308,361, June 12, 1943, and in the copending application of Robert E. Fearon, Serial Number 325,880, filed March 25, 1940.

The prospecting device 24 is connected to a signal transmitter or recording device 23 which includes a means for directly recording signals from the prospecting device upon a time driven sheet, or which comprises a suitable transmitter of high audible or radio frequency signals capable of transmitting the signals from the prospecting device when within the well bore to suitable recording or indicating equipment located at the surface. It is preferred, instead of transmitting the signals to remotely located recording equipment, to record the signals from the geophysical prospecting device within the capsule directly upon a tape or record sheet moved in accordance with motion of the instrument during use, thus providing an index of the character of the formations directly correlated with an indication of the position of the instrument. This effect is readily accomplished by driving the tape with a suitable timing mechanism imparting uniform rate of movement thereto, and lowering the drill string at a uniform rate within the well bore, permitting comparison of the rates of movement of the instrument and the string to give accurate indications of the instrument position. If it is desirable to transmit signals from the prospecting device directly to surface indicating or recording equipment, the same can be achieved by using a suitable signal generator controlled by the prospecting device. For example, an audible signal, preferably of high frequency, can be transmitted through the well mud or through the metallic drill stem, utilizing, if desired, the principles disclosed in the patent to Robert F. Davis, No. 2,285,809, June 12, 1942, or if preferred a radio signal can be transmitted from the prospecting device to surface equipment, if desired, in accordance with the principles disclosed in the copending applications of Robert E. Fearon, S. N. 311,218 and S. N. 311,219, both filed December 27,

1939. It will be understood that signals transmitted from the subsurface prospecting instrument to surface recording equipment, at the time of recording will be correlated with indications of movement of the prospecting device within the well bore.

The control device 22 serves to initiate and to terminate operation of the recording or signal transmitting unit 23 and is provided to prevent 10 operation of the prospecting device before it reaches its preselected position within the drill stem or during the time the instrument is being withdrawn from said position. This control mechanism can be, if desired, a simple time control 15 capable of causing the recording equipment to operate at a preselected time for a predetermined time interval thereafter. The control mechanism also, if desired, can be operated by reception of high audible frequency signals 20 transmitted through the drill stem or well mud to a microphone or other suitable receiving device connected with appropriate amplifiers, relays or equivalent mechanism to control the operation of the recording mechanism. Or, if 25 desired, in like manner, a radio receive capable of detecting signals transmitted from surface equipment can be used to control the operation of the prospecting device. As a further possible modification, within the scope of the invention, 30 a purely mechanical control can be used, if desired, which would cause the recording mechanism to operate when placed in its preselected position within the drill stem and to cease to function when removed therefrom by suitable 35 interengaging members upon the instrument and within the drill stem. A mechanical control, functioning by movement of well mud in the vicinity of the instrument, can also be employed to control the operation of the recording equipment.

40 From the foregoing description, it will be seen that the present invention provides a method of geophysical prospecting that can be practiced during, and without interruption of the usual course of well drilling operations, thus providing 45 the drilling crew and operators with the advantages accruing from immediate knowledge of the nature of strata being traversed by the bore.

I claim:

1. Method of simultaneously drilling and prospecting a well bore that comprises the following 50 sequence of operations: partially withdrawing the drill string from operative position within the well bore; placing a prospecting instrument of a type capable of measuring radiations which will pass through the drill stem within the partially withdrawn drill stem near the drill bit; returning the drill string to its original position at a measured rate of movement; removing the prospecting instrument from the drill stem; and 55 correlating indications from the prospecting instrument with measurements of movement of the drill string to obtain indications of the character 60 of formations traversed by the well bore.

2. Method of geophysical prospecting within a 65 well bore during usual well drilling operations that comprises placing a prospecting instrument of a type capable of measuring radiations which will pass through the drill stem within the base of the drill stem while the drill string is in raised 70 position for addition of a stem element thereto, returning the string to operative position at a measured rate of movement, removing the instrument from the stem after the string is returned to drilling position, and correlating indications from the prospecting device with said

measurements of the return movement of the drill string as an indication of the nature of traversed strata.

3. Method of simultaneously drilling and prospecting a well bore that comprises the following sequence of operations: partially withdrawing the drill string from operative position within the well bore; placing a radiation-sensitive prospecting instrument of a type capable of measuring radiations which will pass through the drill stem at a preselected position within the partially withdrawn drill stem near the drill bit; returning the drill string to its original position at a measured rate of movement; removing the prospecting instrument from the drill stem; and correlating indications from the prospecting instrument with measurements of movement of the drill string to obtain indications of the character of formations traversed by the well bore.

4. Method of geophysical prospecting within a well bore during usual well drilling operations that comprises placing a radiation-sensitive prospecting instrument of a type capable of measuring radiations which will pass through the drill stem at a preselected position within the base of the drill stem while the drill string is in raised position for addition of a stem element thereto, returning the string to operative position at a measured rate of movement, removing the instrument from the stem after the string is returned to drilling position, and correlating indications from the prospecting device with said measurements of the return movement of the drill string as an indication of the nature of traversed strata.

5. Method of simultaneously drilling and prospecting a well bore that comprises the following sequence of operations: partially withdrawing the drill string from operative position within the well bore; placing a high pressure ionization chamber through which a current flows proportional to radiation impinging thereon within the partially withdrawn drill stem near the drill bit; returning the drill string to its original position at a measured rate of movement; measuring the current flowing through the ionization chamber during the return of the drill string to its original position; and correlating measurements of said current with measurements of the movement of the drill string to obtain indications of the character of formations traversed by the well bore.

6. Method of simultaneously drilling and prospecting a well bore that comprises the following sequence of operations: partially withdrawing the drill string from operative position within the well bore; placing a prospecting instrument sensitive to gamma radiation emanating from geological formations within the partially withdrawn drill stem near the drill bit; returning the drill string to its original position at a measured rate of movement; removing the prospecting instrument from the drill stem; and correlating indications from the prospecting instrument with measurements of movement of the drill string to obtain indications of the character of formations traversed by the well bore.

7. Apparatus useful in the simultaneous drilling and prospecting of a well bore that comprises a fluid-tight capsule capable of being placed within an ordinary drill stem, a geophysical prospecting device within said capsule capable of detecting characteristics of geological formations by measuring radiations which will pass through the drill stem, means for providing a record of indications from said prospecting instrument, and control means within said capsule for regulating operation of the prospecting device.

8. Apparatus useful in the simultaneous drilling and prospecting of a well bore that comprises a fluid-tight capsule capable of being placed within an ordinary drill stem, a geophysical prospecting device sensitive to radiation within said capsule capable of detecting characteristics of geological formations by measuring radiations which will pass through the drill stem, means for providing a record of indications from said prospecting instrument, and control means within said capsule for regulating operation of the prospecting device.

9. Apparatus useful in the simultaneous drilling and prospecting of a well bore that comprises a fluid-tight capsule capable of being placed within an ordinary drill stem, a geophysical prospecting device of the type including a high pressure ionization chamber sensitive to gamma radiation within said capsule capable of detecting characteristics of geological formations, means for providing a record of indications from said prospecting instrument, and control means within said capsule for regulating operation of the prospecting device.

CHARLES A. MOON.
